CHARLES L. SPENCER, OF PROVIDENCE, RHODE ISLAND.

Letters Patent No. 87,218, dated February 23, 1869.

APPARATUS FOR CONVERTING MOTION.

The Schedule referred to in these Letters Patent and making part of the same.

To all whom it may concern:

Be it known that I, CHARLES L. SPENCER, of the city and county of Providence, in the State of Rhode Island, have invented a new and useful Improvement in Apparatus for Converting Motion; and I do hereby declare the following is a full, clear, and exact description thereof, reference being had to the accompanying drawings, and to the letters of reference marked thereon, in which—

Figure 1 represents my improvement when opened.

Figure 2 represents the same when the treadle is at the lowest point.

Figure 3 represents it when the treadle is at the highest point.

Figures 4, 5, and 6, represent a pawl-arrangement.

Figure 7 shows the front view of the lower or flexible parts of the connecting-rods.

In the accompanying drawing, A A, fig. 1, are two rods, curved at their upper ends, the lower ends of which are made flat and flexible.

These rods are held together and in place, by means of the clamp B, with rivets, as shown in fig. 7, forming a double flexible connecting-rod, a hole being drilled through the bottom part of clamp B, figs. 1, 2, and 3, for the purpose of connecting to a treadle by a pin, the treadle being represented in same figures by dotted lines.

These flexible rods may be constructed of one piece of metal, having central connection of sufficient thickness for their use and wear.

When used in connection with two reciprocating

pawls, attached on a shaft, a rotary motion is produced with the connection of the treadle.

Figs. 4, 5, and 6, represent the pawl-arrangement, all of which is shown in Letters Patent issued to me, March 4, 1862, No. 34,597, and used in connection with a pair of jointed tongs, with a separate spring between them; but the same constitutes no part of the present invention, and are shown as suitable devices to be used in connection with the flexible connecting-rods.

My improvement consists in the employment of a double flexible connecting-rod, dispensing with a joint and separate spring, in combination with pawls described in the patent referred to, or any other suitable pawl-and-ratchet mechanism. So that at all times, from the extreme points, as indicated by the dotted lines in figs. 1, 2, and 3, the line of action will be direct and positive from the central connection of the treadle to the centre of the driven shaft.

With this improvement, proved by actual experiment, the double flexible connecting-rod works nearer to the centre, obtaining more velocity to the shaft, with no liability of hanging upon the dead-point.

What I claim as my invention, and desire to secure by Letters Patent of the United States, is—

The two flexible connecting-rods A A, in combination with any suitable pawl-and-ratchet mechanism, for converting a reciprocating into a rotary motion, substantially as described.

Witnesses: CHARLES L. SPENCER.
